UNITED STATES PATENT OFFICE.

JENS O. JENSEN, OF NEW YORK, N. Y.

PROCESS OF AND APPARATUS FOR PREPARING CRUDE OIL FOR DISTILLATION.

1,268,721.

Specification of Letters Patent. Patented June 4, 1918.

Application filed February 24, 1917. Serial No. 150,662.

To all whom it may concern:

Be it known that I, JENS O. JENSEN, a subject of the King of Denmark, residing at New York, in the county of New York and

5 State of New York, have invented a certain new and useful Improvement in Processes of and Apparatus for Preparing Crude Oil for Distillation, of which the following is a specification.

10 In the distilling of crude oil, it is known that the presence of water in certain oils causes foaming, and greatly retards the speed of distillation. My present invention is a process and an apparatus, whereby I am able to remove all of the water and crude naphtha and similar low boiling fractions from the crude oil prior to the delivery of said oil to the still, or prior to the delivery of said oil to a storage tank, where it may 15 be retained to await later distillation. I have built a commercial plant, substantially as herein described, wherein I have carried my aforesaid process into practical effect, and I have found as a result that I have 20 increased the normal output of the plant by forty-five per cent., without increasing the expenditure of fuel.

My process consists broadly in first heating the crude oil to a temperature above the 25 boiling point of water, and preferably above 400° Fahr., and then delivering said heated oil to an evaporator, wherein it is caused to form thin films or sheets. All of the water and most of the low boiling fractions are thus evaporated, the vapor passing off to a suitable condenser. After the evaporation, the crude oil leaves the evaporator at a 30 temperature of about 40° Fahr. below the temperature at which it enters said evaporator, and may then pass either directly to a still, or first to a storage tank, and then to a still, as desired. In either case, however, the temperature of the oil must be maintained above the boiling point of water.

45 Where the crude oil contains considerable low boiling fractions which may not all be removed by one evaporation, I subject the oil coming from the first evaporator to a second evaporation for the removal of whatever of said fractions may remain in it. From the second evaporator the vapor is 50 taken to the condenser, as before, while the

crude oil, as before, goes to the storage tank, or to the still directly, as may be desired. The vapors from the condenser are conducted to a separate storage tank.

While the oil is in the storage tank, it is important that its temperature—although above the boiling point of water—should be less than that of the flash point of said oil. 60 To this end, I cool the accumulated oil in the tank by an exchange of temperature between said oil and the cold oil flow coming from the source of supply to the heating means, and thus utilize the excess temperature existing in the tank.

In order to maintain the temperature of the oil in the storage tank above the boiling point of water, I provide means for heating insulating the tank, or for directly heating 70 the contents, as hereinafter described.

For carrying my process into practical effect, I have devised an apparatus which is illustrated in the accompanying drawing, of which Figure 1 is a general diagrammatic view. Fig. 2 shows the heater for crude oil partly in vertical longitudinal section and partly in side elevation. Fig. 3 is an elevation of the evaporator, with the upper portion of the casing removed to show the internal construction. Fig. 4 is a horizontal section of the storage tank on the line Y, Y of Fig. 5. Fig. 5 is a vertical section of said tank on the line X, X of Fig. 4. Fig. 6 is a side elevation of the delivery end of pipe 85 b within the evaporator, and showing said end in trough form.

Similar letters and numbers of reference indicate like parts.

The crude oil is pumped to the heater A 90 through the pipe 1 which is connected to the source of supply. Said heater comprises a casing 2, Fig. 2, of masonry, divided into compartments 3, 4 by a partition 5. In compartment 4 is a baffle-plate 6 extending upwardly from the bottom of the casing, and in compartment 3 is a similar baffle-plate 7. Extending across the heater casing and preferably through the walls thereof are tubes 8, connected in series to form a continuous 95 tube system by elbows 9. Said elbows are outside of said casing and on opposite sides thereof. The crude oil entering from pipe 1 passes upwardly through the tubes 8 on

Projecting into the container 15 from the bottom wall 16 thereof is a spider 25 the arms of which rise from the said bottom wall and converge to support the sleeve 26 of the spider axially of the container. At its lower end this sleeve is preferably connected with the said bottom wall. Slidably fitted through the spider sleeve 26 as well as through the cap 18 of the container 15 is 10 an axially arranged valve stem 27. This valve stem projects freely through the bottom wall 16 and at its lower end carries a valve 28 adapted to overlie the discharge openings 17 in the said bottom wall. The 15 valve 28 may be formed of leather or other suitable material and supporting the said valve is a metallic washer 29 held by a cotter-pin or other suitable fastening device 30 fitted through the lower end of the valve 20 stem for connecting the washer and valve thereto. Surrounding the valve stem within the container 15 is a helical spring 31. One end of this spring bears against a washer 32 carried by the valve stem to rest 25 against the spider 25 while the opposite end of the said spring engages a similar washer 33 held upon the valve stem by a cotter pin or other suitable fastening device 34. Thus it will be observed that the spring 31 will 30 normally maintain the valve 28 closed.

As will now be readily understood, the container 15 may, by simply removing the cap 18, be filled with a lubricant. When it is desired to introduce a portion of the lubricant 35 into the crank case of the engine this result may be readily accomplished by simply depressing the valve 27 to unseat the valve 28 when the lubricant will flow through the discharge openings 17 of the container into the 40 discharge pipe 19 and through the breather pipe 11 to the engine crank case. Upon the release of the valve stem, the valve 28 will be immediately closed by the spring 31. This provides a very simple and convenient 45 arrangement for lubricating the engine while at the same time the container 15 will form an auxiliary reservoir for the engine lubricant. Removably fitted within the discharge pipe to rest upon the shoulder 20 thereof is 50 a suitable screen 36 adapted to strain the lubricant as it passes into the engine crank case. In order that air may be admitted to the engine crank case, the discharge pipe 19 is, at a point slightly below the bottom wall 55 16 of the container, provided with a series of circumferentially spaced openings 37 through which the engine may freely breathe and arranged to overhang the said openings is a guard flange 38. This flange 60 is preferably integral with the discharge pipe and will tend to prevent dirt or other foreign matter from finding its way into the discharge pipe to thence be drawn into the engine crank case. Furthermore, the 65 screen 36 will also perform a function in

this regard as it will be seen that the said screen will further tend to prevent the passage of any foreign matter through the breather pipe.

It will therefore be seen that we provide 70 a particularly simple and efficient construction for the purposes set forth while at the same time the device is of such nature that it may be readily applied to a conventional engine of the Ford type without the necessity for any structural change therein. 75

Having thus described the invention, what is claimed as new is:

1. The combination with an internal combustion engine having a breather pipe, of a 80 lubricator for the engine including a container, a discharge pipe extending therefrom and connected with the breather pipe to support the container thereon, the said discharge pipe being formed with an opening admitting air into the breather pipe, and means associated with the container for controlling the flow of a lubricant from the container into the breather pipe. 85

2. A lubricator of the character described 90 including a container, a discharge pipe extending therefrom and provided with an opening, and a valve carried by the container for controlling the flow of a lubricant therefrom into the said discharge pipe, 95 the discharge pipe being adapted for operative connection with the crank case of an engine for supplying lubricant thereto upon the actuation of the said valve with the said opening disposed to admit air into 100 the engine crank case.

3. A lubricator for internal combustion engines including a container, a discharge pipe extending therefrom, the said container being formed with a bottom wall provided 105 with an opening communicating with the discharge pipe, a spider rising from the said bottom wall, a valve stem slidable through the said spider, a valve carried by the valve stem to seat against said bottom wall and 110 close the said opening, and yieldable means associated with the valve for normally urging the valve to closed position. 110

4. A lubricator of the character described including a container, a discharge pipe extending therefrom, binding means adjustable upon the discharge pipe, and means associated with the container for controlling the flow of a lubricant from the container into the discharge pipe, the said discharge pipe 120 being adapted to fit within an engine breather pipe having a fastening device engaging the said discharge pipe for connecting the lubricator with the breather pipe with the said first mentioned means coacting with the breather pipe for binding the said discharge pipe in engagement with the said fastening device. 125

5. A lubricator of the character described including a container, a discharge pipe ex- 130

to the desired temperature above the boiling point of water.

In order to prevent the temperature of the oil accumulated in tank D from falling below the boiling point of water, I may make the casing of said tank double, with an intervening space 28 between the side and top walls. Where the conditions are such as that the heat insulation of the tank 10 is sufficient to prevent the above noted loss of temperature during the time the accumulated oil remains in tank D before going to the still, I may fill the space 28 with any heat insulating material—such as magnesia, 15 or ashes. Where it is desirable directly to heat the oil in tank D, I may cause a hot gas—such as live steam—to circulate through said space, entering, for example, by inlet 29, and escaping by outlet 30; or I 20 may introduce a plurality of loop ducts 31 (three here shown) into the tank, said ducts having their ends connected to a pipe 32, through which steam or hot gas may be caused to pass. Each duct has valves 33, 34 25 outside the casing, and between the duct ends and in pipe 32 is a valve 35. The valves 33, 34, 35 are operated in the same way as valves 25, 26, 27 to cause the current in pipe 32 to pass through one or more ducts 30 31 at will, and so regulate the heating effect of the steam.

The tubes 8 of heater A may be greater in length than the width of the heater, and, therefore, by disconnecting the elbows 9, 35 each tube, in case of injury, may be separately drawn out from the heater casing.

For the purpose of regulating the temperature in heater A, I may provide a valve in pipe c—as, for example, at N—for controlling the supply of oil to the burners 12; or instead of said valve, I may substitute any known automatic device for regulating the flow of said oil to said burner.

I claim:

45 1. The process of preparing crude oil for distillation, which consists in heating said oil to a temperature above 400° Fahr., removing the water and low boiling fractions therefrom, and delivering said oil to the still 50 at a temperature above 212° Fahr.

2. The process of preparing crude oil for distillation, which consists in heating said oil to a temperature above 400° Fahr., evaporating water and low boiling fractions 55 therefrom, subjecting said oil to a second evaporation to remove any low boiling fractions therein remaining, and delivering said oil to the still at a temperature above 212° Fahr.

60 3. The process of preparing crude oil for distillation, which consists in, first, subjecting a current of crude oil to a temperature above the boiling point of water, second, evaporating water and low boiling fractions 65 from said heated oil, third, accumulating

said oil at a temperature above the boiling point of water in a receptacle, and, fourth, cooling said accumulated oil by temperature exchange with a current of cold oil until the temperature of said oil while still above the 70 boiling point of water is reduced below the flashing temperature of said oil.

4. The process of preparing crude oil for distillation, which consists in, first, heating said oil to a temperature above the boiling 75 point of water, second, evaporating water and low boiling fractions from said heated oil, third, accumulating said oil in a receptacle at a temperature above the boiling point of water, and, fourth, cooling said accumulated oil to a temperature still above the boiling point of water but below the flash point of said oil.

5. An apparatus for preparing crude oil for distillation, comprising means for heating said oil, means for evaporating water and low boiling fractions from said heated oil, a tank receiving said oil from said evaporating means, and means for maintaining said oil in said tank at a temperature 80 above the boiling point of water.

6. An apparatus for preparing crude oil for distillation, comprising means for heating said oil, an evaporator receiving said heated oil from said heating means, a tank 95 receiving said oil from said evaporator, and means disposed within said tank for heating said oil.

7. An apparatus for preparing crude oil for distillation, comprising means for heating said oil, an evaporator receiving said heated oil from said heating means, a tank receiving said oil from said evaporator, and a jacket on the exterior of said tank.

8. An apparatus for preparing crude oil for distillation, comprising means for heating said oil to a temperature above the boiling point of water, means for evaporating water and low boiling fractions from said heated oil, a tank receiving said oil from 110 said evaporating means, and means for cooling the oil accumulated in said tank.

9. An apparatus for preparing crude oil for distillation, comprising means for heating said oil, means for evaporating water 115 and low boiling fractions from said heated oil, a tank receiving said oil from said evaporating means, and means in said tank for cooling the oil therein.

10. An apparatus for preparing crude oil for distillation, comprising a conduit for oil circulation, a heater for said oil receiving said oil from said conduit, an evaporator for removing water and low boiling fractions from said heated oil, a tank receiving said 125 oil from said evaporator, and a duct within said tank connected to said conduit for circulating cold oil through said accumulated oil to cool the same.

11. An apparatus for preparing crude oil 130

for distillation, comprising a conduit for oil circulation, a heater for said oil receiving said oil from said conduit, an evaporator for removing water and low boiling fractions from said heated oil, a tank receiving said oil from said evaporator, a plurality of ducts within said tank connected to said conduit for circulating cold oil through said accumulated oil to cool the same, and means

for directing the flow of said cold oil through 10 one or more of said ducts.

In testimony whereof I have affixed my signature in presence of two witnesses.

JENS O. JENSEN.
